UNITED STATES PATENT OFFICE

ZAKARIAS N. BERGMAN, OF SEATTLE, WASHINGTON, ASSIGNOR OF ONE-HALF TO
GEORGE M. FERGUSON, OF SEATTLE, WASHINGTON

LOCK NUT

Application filed October 21, 1929. Serial No. 401,178.

One of my objects is to provide an efficient locking means for holding nuts upon bolts, and to prevent their becoming loosened, and one which is cheap, lending itself to quantity production by automatic machinery, and which is simple to place in operative position, and one which, in case of necessity, may be disengaged, and from which the nut can be backed off the bolt, the threads not being injured to an extent to prevent this.

More specifically, it is my object to provide a locking pin of wedge-like character, having means to present a sharp edge, or serrations, to the threads of a bolt, the serrations being so disposed that they will not sink into and inter-engage with the threads of the bolt.

A further object is to provide a means whereby such a lock nut will cinch up and hold the nuts firmly in place by a type of wedging action, in such manner and so positioned that there is a virtual three-point suspension, or three points of application of greatest force.

My invention comprises the novel parts and the novel combination and arrangement thereof, as is shown in the accompanying drawings, described in the specification, and as will be more particularly defined by the claims which terminate the same.

In the accompanying drawings I have shown several forms of my invention.

Figure 1 is a plan view of my lock nut combination, and Figure 2 is a section thereof on the line 2-2 of Fig. 1.

Figure 3 is a side elevation of a preferred form of my locking pin, and Figure 4 is a transverse section therethrough, on the line 4-4 of Figure 3.

Figure 5 is a side elevation of my lock nut combination.

Figure 6 is a plan view of the nut, arranged according to my invention.

Figure 7 is a side elevation of a modified form of my lock nut combination, and Figure 8 is a section therethrough, on the line 8-8 of Figure 7.

Figure 9 is a side elevation of a further modified form. Figure 10 is a section through the form shown in Figure 9, while

Figure 11 is a similar section through a slight further modification.

One of the drawbacks of proposed lock nut arrangements has been the necessity of seriously deforming the bolt itself, either during or after it has been manufactured, as by cutting a groove in it, or by the insertion of the locking means. According to my invention, there is no deformation of the bolt which would involve a milling operation, but there is only required the cutting or the formation of an axial, or substantially axial, groove in the aperture of the nut itself. This can be readily incorporated in the nut in the course of its manufacture, by automatic machinery, and adds little or nothing to the cost of the nut. The bolt is deformed scarcely at all, and can be used with or without the locking arrangement.

To illustrate my invention I have shown the bolt 1, having a head 10 and a threaded portion 11. Upon this is threaded the usual nut 2, having the threaded aperture 21, within which the threaded end 11 of the bolt 1 is received to hold together such objects as the plates 3 and 30. A washer 31 may be employed, also, if desired.

As has been stated, an axial groove or grooves 20 is formed in the aperture 21, preferably cutting through the bottom of the threads in this aperture. Within this groove 20 is received a locking pin 4, which is preferably tapered, and is so shown in the drawings. While I may use a single pin, as shown in Figures 7 and 8, I prefer to use two pins, and prefer that these two pins be jointed at 43 in the form of a U-shaped staple, as is best seen in Figure 3. As may be seen in Figure 4, the back side of the pin 4 is plane, as indicated at 40, while its inner or front edge is inclined to be sharpened, as indicated at 41. The plane back edge 40 seats in the plane bottom of the groove 20, which is preferably without any taper, and this engagement of the plane surfaces 40 and 20 prevents tilting of the pin 4, and causes the sharp edge 41 to be presented always to the threads 11 of the bolt 1. This feature, of course, is not of as great importance in the staple form

of the locking pin as in the form where single pins only are used.

In either form of the pin I prefer that the forward edge 41 be serrated, as is indicated at 42, thus to provide saw-like teeth, which, in a sense, cut into the tops of the threads 11 of the bolt. Such a line of cutting is indicated at 14 in Figure 2, and it will be observed that this is not sufficient to seriously affect the threads. The nuts can still be turned off (the pins 4 having been first removed) without any particular effort, and threaded on again, yet the engagement is sufficient to obtain tight locking of the nut to the bolt. This, of course, is assisted by the wedging action of the tapered pin 4 in its straight groove 20. It should be noted, also, that the serrations 42 are inclined with respect to the axis of the pin 4, as may be best seen in Figure 3, and the purpose of this is to present an inclined edge to the edges of the threads 11, so that the serrations will not sink into the grooves between the threads of the bolt, and thereby lose its wedging or holding action. Because of the inclination of these serrations relative to the threads of the bolt, the pin will ride always on the top of the bolt, yet there will be permitted the cutting action of the serrations.

I prefer that the length of the locking pin 4 be such that it will tend to extend somewhat past the inner surface of the nut 2. The effect of this, when it is pressed in, is to somewhat upset its tip, which tends to project, and this will tend to fill the inner end of the groove 20, or to cause the tip to curl over and perhaps follow the groove between threads 11, as is illustrated in Figure 8. This serves to retain the pin 4 in place, yet it can be withdrawn if that is necessary. Especially, it can be withdrawn by inserting a tool such as a screw driver under the section 43, which joins the two staple-like pins 4.

It is not strictly essential that the grooves 20 be disposed parallel with the axis of the nut, though this is preferable, both from reasons of ease of insertion and withdrawal of the locking pin, and because of economies which can be effected thereby in the manufacture of the nut. However, in Figures 9 and 10 I have shown the groove 20' as slightly inclined, and in Figure 11 have shown the groove 20' as curved slightly.

Using the two pins, whether joined by the section 43 or independent of one another, the nut is drawn to one side, since these grooves are arranged upon the same side of a diametrical plane, and the side of the nut midway opposite between these two grooves is drawn tightly into the threads of the bolt, so that there are provided three lines of greatest force, in the two grooves and at the side midway opposite the two grooves. This firmly holds the nut to the bolt, and compensates for any possible looseness of the nut upon the bolt.

What I claim as my invention is:

1. In combination with a bolt, a nut threaded thereon, the aperture of said nut having a groove through it, and a tapered locking pin triangular in cross section held in said groove and having an edge of said pin adjacent the bolt, the locking pin, towards the bolt, being serrated to cut through the edges of the bolt's threads, and said serrations being diagonally disposed to prevent interengagement thereof with the thread. 70

2. In combination with a bolt, a nut threaded thereon, the aperture of said nut having two axial grooves through it, at one side of a diametrical plane, and a tapered locking pin wedged in each of said grooves, and engaging the threads of the bolt, thereby forming a tight fitting three point contact. 80

3. A lock nut combination as in claim 2, the two pins being joined to form a U-shaped staple. 85

Signed at Seattle, Washington, this 12th day of October, 1929.

ZAKARIAS N. BERGMAN.
